UNITED STATES PATENT OFFICE

157,182

SPOTLIGHT HOUSING

Tom Nerman, Park Ridge, Ill.

Application August 21, 1948, Serial No. 148,233

Term of patent 14 years

(Cl. D48—32)

To all whom it may concern:

Be it known that I, Tom Nerman, a citizen of the United States, residing at Park Ridge, in the county of Cook and State of Illinois, have invented a new, original, and ornamental Design for a Spotlight Housing, of which the following is a specification, reference being had to the accompanying drawing, forming a part thereof.

In the drawing:

Fig. 1 is a side elevational view of a spotlight housing, showing my new design;

Fig. 2 is a front elevational view of the same;

Fig. 3 is a top plan view of the housing; and

Fig. 4 is a rear elevational view of the housing.

The dominant features of my design reside in the portions shown in full lines.

I claim:

The ornamental design for a spotlight housing, substantially as shown and described.

TOM NERMAN.
